UNITED STATES PATENT OFFICE.

ROBERT J. ALLEN, OF NEW YORK, N. Y.

BOILER-BRICK.

1,168,697.

Specification of Letters Patent.

Patented Jan. 18, 1916.

Application filed September 25, 1915. Serial No. 52,733.

To all whom it may concern:

Be it known that I, ROBERT J. ALLEN, a subject of the King of Great Britain, residing in the borough of Manhattan, city, county, and State of New York, have invented certain new and useful Improvements 5 in Boiler-Bricks, of which the following is a specification.

This invention has for an object to provide an improved brick for use in setting boilers, particularly those wherein the header to which the tubes are attached presents a sinuous conformation. In placing the brickwork at the headers having the 15 formation referred to it is necessary to chip the ends of the brick by hand and set each individual brick at its proper place. This method of procedure is not only expensive on account of the large amount of hand 20 work necessarily required, but is also unsatisfactory owing to the inability of the workman to chip the bricks absolutely in conformity to the curved outlines of the part against which they are to rest. This feature 25 of disadvantage is also enhanced by the fact that all bricklayers are not sufficiently expert craftsmen to do the work with the necessary accuracy. Still a further disadvantage is the length of time necessarily 30 employed. In buildings requiring the use of boilers, to which this present invention is applicable, when the construction work comes to the period at which the boiler is to be set, it is very desirable to advance the 35 work rapidly. In some boilers the header is in a substantially vertical position, and the tubes are obliquely disposed with relation to the header. This not only requires that the brick be chipped to conform to the 40 sinuosity of the header, but that the chipping also be at an angle. In other forms of boiler the tubes are perpendicular to the header, which is arranged in an oblique position relative to the vertical, in which instance the chipped header bricks must also 45 have an oblique disposition in the wall. My invention embodies brick for use in connection with both forms of boiler.

In the drawings accompanying this specification one practicable embodiment of the invention is illustrated.

In such drawings, Figure 1 represents in perspective one of the improved bricks, particularly disposed header; Fig. 2 is a side view 55 of the brick shown in Fig. 1; Fig. 3 is a per-

spective view of the brick designed for use in connection with an obliquely disposed header; and Fig. 4 is a vertical cross-section through the walls provided with my improved brick and boiler headers. 60

In Fig. 4 boiler headers 5 are represented. These boiler headers may be assumed to be disposed in substantially vertical positions. The outer surfaces of these headers present a sinuous line 6. According to the practice 65 of boiler setting prior to my invention it was necessary in laying up the wall to chip the ends of the bricks one by one and set them in position adjacent the headers, and fill in the more or less irregular outlines and 70 interstices with some suitable cement. The boiler tubes being disposed obliquely to the header, present upon the opposite or respective sides of the complement of boiler tubes what in practice is referred to as right and 75 left angles. In this view there are shown four units of sinuously formed header bricks for covering the header at each side. As a matter of fact, these units are really two pairs of similar units 7, 7—7', 7'. 80

One of the improved bricks for use in connection with the vertically disposed header is illustrated in Figs. 1 and 2. In this view the body of the brick 8 is shown provided with a beveled and sinuous edge 9 adapted 85 to set against the sinuous outline 6 of the header and to cover a considerable portion thereof, in the illustration at least more than one complete in or out curvature. In practice I have found it desirable to make these bricks substantially eighteen inches high for use in connection with existing forms of Babcock & Wilcox boilers. In any event the brick preferably occupies a space 90 equal to a plurality of ordinary bricks. In 95 the illustrated example each header brick unit is designed to occupy a vertical space equivalent to seven ordinary set brick.

Wall building at an obliquely disposed header involves, in addition to the problems 100 discussed in connection with the vertical header, chipping to the proper level the brick which abut both sides of the obliquely disposed row of header brick. A combined header and supporting wall unit for doing away with the two brick cutting operations just referred to is illustrated in Fig. 3. The header portion 10 corresponds in height to 105 and is designed to supplement, in the present illustrative example, seven ordinary 110

brick when set in cement. This header portion is shown provided with a sinuous edge 11 for fitting a plurality of reverse curves of the sinuous sided header. The header portion 5 brick portion is disposed obliquely on its wall forming body portion 12 at an angle corresponding to the obliquity of the boiler header. The header engaging portion of the brick is shown obliquely disposed on the 10 body portion and protruding therefrom. The oblique disposition of the header portion 10 when built up in the usual form of a plurality of brick requires, as above stated, the oblique chipping or cutting of the abutting 15 bricks in the wall. The portions 12', 12" of the illustrated brick are the portions which take the place of a plurality of chipped brick, thereby reducing the time and expense of putting up the brick work, and 20 also assures a firmer and more accurate job.

It is to be understood that the brick shown herein and described are illustrative examples of the invention designed to meet particular problems, and that changes may be 25 made in details within the scope of the

claims without departing from the spirit of the invention.

What I claim is:—

1. A boiler brick provided with a sinuously disposed face for engaging and conforming to the sinuous side of a boiler header, such sinuous face embodying a plurality of reverse curves, and equal in height to a plurality of ordinary brick. 30

2. A boiler brick comprising a body portion and a protruding portion obliquely disposed thereon, equal in height to a plurality of ordinary brick, said protruding portion being provided with a sinuously disposed face for engaging and conforming to 35 the sinuous side of a boiler header and embodying a plurality of reverse curves. 40

In witness whereof, I have hereunto signed my name in the presence of two subscribing witnesses.

ROBERT J. ALLEN.
